UNITED STATES PATENT OFFICE.

CONRAD B. KRAUSE, OF CLEVELAND, OHIO.

PUMP.

Application filed January 1, 1926. Serial No. 78,724.

This invention relates to pumps and more particularly to pumps especially adapted for use as compressors in connection with refrigerating apparatus.

5 It is one of the objects of the invention to provide a pump, of relatively small capacity, that will be efficient in operation and so designed as to have a minimum of wearing surfaces and these points of wear so arranged that the wear will not materially affect the operation of the pump for relatively long periods of time. The invention has particular reference to domestic refrigeration apparatus and it is a further object 10 to provide a construction that will be practically noiseless in operation and avoid the pulsations in the compressed fluid, which is one of the objectionable features of present types of pumps of small capacity.

20 A further object of the invention is to provide a double-acting pump that will require very little, if any, more space than a single-acting pump of the same capacity.

25 A further object of the invention is to provide a pump of such simple design and construction that it may be manufactured on a commercial scale at a comparatively low cost.

Other objects of the invention and the features of novelty will be apparent from the 30 following description taken in connection with the accompanying drawings, of which:

Fig. 1 is a side elevation of a pump embodying my invention;

Fig. 2 is a horizontal section on the line 35 2-2 of Fig. 1;

Fig. 3 is a section on the line 3-3 of Fig. 1;

Fig. 4 is a vertical section through the axis of the pump cylinder;

40 Fig. 5 is an end elevation of the outboard bearing for the crank shaft; and

Fig. 6 is a section on the line 6-6 of Fig. 5.

45 Referring to the drawings, 10 indicates one of the housing sections having a substantially flat end against which there is secured the hollow housing section 11, these sections having peripheral flanges 12 and 13, respectively, which are secured together by screws or bolts 14. The flanges 12 and 13 are accurately machined so as to fit together, as shown at 15. A cylinder 16 is arranged within the section 11, of the housing, and has bearing surfaces 17 and 18, at its ends, to fit against accurately machined surfaces at the end of the housing section 10, which are

in the same plane as the surfaces 15, so that all of these surfaces, on the end of the section 10, may be machined off by a single operation. The cylinder 16 has oppositely projecting trunnions 19 and 20, the trunnion 19 being mounted in a bearing sleeve 21, in the housing section 10, and the trunnion 20 being mounted in a bearing sleeve 22, in the housing section 11. The boss 23, carrying the sleeve 22, has its outer end closed by a plug 24. The cylinder 16 has a removable head 25 that is secured thereto by the screws 26, and the surfaces 17 and 18 are equally spaced on opposite sides of the trunnion 19. 60

65 A crank shaft 27, arranged parallel with the trunnions 19 and 20, is mounted in a bearing sleeve 28, in the housing section 10, and a stuffing box 29 is provided for the purpose of preventing leakage along the shaft 27, the packing of this stuffing box being tightened by means of the gland nut 30. A pair of parallel studs 31 and 32 are secured in the housing section 10 by a pin 33 and are arranged in accurate parallelism with 70

the shaft 27. An out-board bearing 34 is carried by the studs 31 and 32 and secured thereon by a pin 35, the arrangement permitting the bearing 34 to be readily removed, for the purpose of permitting removal of 80

the nut 30, and then replaced in accurate alignment with the bearing sleeve 28. The bearing 34 supports the shaft 27 and is provided with a depending oil well 36 from

85 which the bearing 34 is lubricated by means of the wick 37. A pulley 38 is secured on the outer end of the shaft 27 with its hub abutting the end of the bearing 34 and cooperates with the head 27', at the opposite end of the shaft to hold the shaft against end-

wise movement. The bearing 34 has an oil-catching flange 39 and a passage 40 for draining the intercepted oil back into the oil well 36. 90

95 Fig. 5 is an end elevation of the outboard bearing for the crank shaft; and

Fig. 6 is a section on the line 6-6 of Fig. 5.

100 Referring to the drawings, 10 indicates one of the housing sections having a substantially flat end against which there is secured the hollow housing section 11, these sections having peripheral flanges 12 and 13, respectively, which are secured together by screws or bolts 14. The flanges 12 and 13 are accurately machined so as to fit together, as shown at 15. A cylinder 16 is arranged within the section 11, of the housing, and has bearing surfaces 17 and 18, at its ends, to fit against accurately machined surfaces at the end of the housing section 10, which are

the shaft 27, a screw 49 being carried by the crank for the purpose of holding the yoke against displacement.

The trunnion 19 has an extension 50 which carries a thrust bearing 51 between which and the bearing sleeve 21 there is a spring 52 for the purpose of firmly and uniformly holding the surfaces 17 and 18 of the cylinder in sealing engagement with the abutting surfaces on the end of the section 10. The outer end of the cavity containing the thrust bearing 51 and spring 52 is closed by the plug 53 so as to prevent leakage.

The cylinder 16 has ports 54 and 55 adjacent its ends so that the piston may travel practically to the ends of the cylinder without covering the ports, thereby permitting a practically complete discharge of the contents upon each stroke. The port 54 operates with an intake port 56 and with a discharge port 57 in the housing section 10. In a similar manner, the port 55 cooperates with an intake port 58 and with a discharge port 59. The discharge ports 57 and 59 are preferably made larger than the other ports mentioned, so as to allow a full discharge of the cylinder contents, on each stroke. The intake port 56 is in communication with a vertically extending port 60 which is drilled in the housing section 10 and has its outer end closed by a plug 61. In a similar manner, the intake port 58 communicates with a vertically extending port 62, which is drilled in the housing section 10 and has its outer end closed by a plug 63. The ports 60 and 62 communicate with a horizontally extending port 64, which is drilled in the housing section 10 from one end and has its outer end closed by the plug 65. The discharge port 57 communicates with a vertically extending port 66 that is drilled in the housing section 10 and has its outer end closed by the plug 67. In a similar manner, the discharge port 59 communicates with a vertically extending port 68 that is drilled in the housing section 10 and has its outer end closed by the plug 69. The ports 66 and 68 communicate with the horizontally extending port 70 that is drilled in the housing section 10 and has a threaded recess 71, at its outer end, to receive a pipe connection for conducting the compressed fluid to the point of use. The housing section 11 has a boss 72 that is provided with a threaded recess 73 to receive a connection for the intake pipe of the pump. A port 74 communicates with the recess 73 and registers with a port 75 in the housing section 10, which communicates with the horizontal port 64. The port 75 has arranged in it a bushing 76 which has a seat 77 for one side of the valve 78, the opposite side of this valve being adapted to cooperate with a seat 79 in the bushing 80. The valve 78 is mounted on a stem 81 which projects

through a stuffing-box 82 and has its outer end squared, as shown at 83, to receive a wrench. The stem 81 is threaded in the housing, as indicated at 84, so as to be moved endwise when it is turned.

The bushing 80 has an interior bore that is slightly larger than the valve stem 81 to permit fluid to flow from a charging port 85 to the inlet port 64. The charging port 85 is normally closed by the plug 86. The housing section 10 has a base 87 adapted to be secured to a suitable support.

The symmetrical arrangement of the surfaces 17 and 18, at equal distances on opposite sides of the trunnion 19, insures against any unbalanced forces tending to tilt the cylinder so as to permit leakage at either of these surfaces. The arrangement of the trunnions 19 and 20, on opposite sides of the cylinder, also tends to hold the cylinder in proper alignment.

The provision of the double-acting valve 78 affords a convenient means for charging the system, with which the pump is associated. When the valve is closed against the seat 77, the pump will draw in a supply of fluid through a connection that is substituted for the plug 86 and when the charging of the system has been completed, the valve 78 is moved so as to be closed against the seat 79 thereby transferring the suction to the port 74.

On account of using a double-acting cylinder and piston and the symmetrical arrangement of the surfaces 17 and 18, about the cylinder trunnions, it has been possible to provide a pump having practically double the capacity of the ordinary single-acting pump, but requiring little, if any, more space than would be required for a single-acting pump. In addition to this, my improved pump has the advantage, over a single-acting pump, of lessening the variations of pressure in the system by doubling the number of suction and discharge strokes in a given time.

Having thus described my invention, I claim:

1. In pumps, the combination of a housing, a cylinder oscillatably mounted in said housing, a double-acting piston in said cylinder having a wrist pin projecting through the side walls of the cylinder, a crank shaft, and a yoke operatively connected with said wrist pin and with said crank shaft for reciprocating the piston.

2. In pumps, the combination of a housing, a cylinder oscillatably mounted in said housing, a double-acting piston in said cylinder having a wrist pin projecting through the side walls of the cylinder, a crank shaft, said cylinder and said housing having cooperating bearing surfaces and inlet and discharge ports therein, spring means for holding said surfaces in contact, and a yoke

operatively connected with said wrist pin and said crank shaft for reciprocating the piston.

3. In pumps, the combination of a housing, a cylinder having a trunnion mounting in said housing on which it oscillates, a double-acting piston in said cylinder having a wrist pin projecting through the side walls of the cylinder, a crank shaft, said cylinder and said housing having cooperating bearing surfaces on opposite sides of said trunnion mounting and inlet and discharge ports therein, spring means for holding said surfaces in contact, and a yoke operatively connected with said wrist pin and said crank shaft for reciprocating said piston.

4. In pumps, the combination of a housing, an oscillating cylinder in said housing, a piston in said cylinder, a crank shaft operatively connected with said piston, a bearing in said housing for said shaft, a stuffing-box surrounding said shaft exteriorly of said bearing, a supporting stud in said housing arranged parallel with said shaft, and a bearing for said shaft carried by said stud.

5. In pumps, the combination of a housing, an oscillating cylinder in said housing, a piston in said cylinder, a crank shaft operatively connected with said piston, a bearing in said housing for said shaft, a stuffing-box surrounding said shaft exteriorly of said bearing, a plurality of supporting studs projecting from said housing parallel with said shaft, and a bearing for said shaft carried by said studs.

6. In pumps, the combination of a housing comprising two sections one of which has a substantially flat end with a plurality of fin-

ished surfaces thereon all in the same plane and the other of which is hollow and provided with marginal surfaces fitting against

surfaces on said end, means for securing said sections together, an oscillating cylinder arranged within the second-mentioned section and having trunnions positioned in aligned bearings in said sections, said cylinder and said end having cooperating bearing surfaces arranged on opposite sides of said trunnions and provided with ports for controlling the flow of fluid to and from the opposite ends of said cylinder, a spring cooperating with one of said trunnions for holding the last-mentioned surfaces in sealing engagement, a double-acting piston in said cylinder, a crank shaft carried by said housing, a yoke operatively connected with said crank shaft, and a pin arranged at right angles to the axis of said trunnions and operatively connecting said yoke with said piston, said cylinder having slots in its side walls in which said pin reciprocates.

7. In pumps, the combination of a housing, an oscillating cylinder having a trunnion mounting in said housing, said cylinder and housing having cooperating bearing surfaces equally spaced and symmetrically positioned on opposite sides of the axis of said trunnion mounting with cooperating inlet and discharge ports in said surfaces, and spring means associated with said trunnion mounting for pressing said surfaces into sealing engagement.

In testimony whereof, I hereunto affix my signature.

CONRAD B. KRAUSE.
